SHOCK ABSORBER FOR ROTARY DRILLS

Walter T. Allen, Cuero, Tex.

Application March 15, 1951, Serial No. 215,793

6 Claims. (Cl. 255—28)

This invention relates to an improved device to attach a drill bit to a shank of the rotary type.

The object of this invention is to provide an improved device for attaching a drill bit on the end of a rotary shank, the device including in addition to a plunger slidable in a body, the plunger and body respectively being provided with means to fasten to a conventional shank and to a conventional bit, a plurality of casings which constitute pistons, the casings being fastened to either the plunger or the body and slidable with respect to the body or plunger, the pistons having an orifice therein to allow restricted flow of fluid to obtain dashpot action and yet permit displacement of the plunger with respect to the body in response to shocks occasioned by use of the bit.

Ancillary objects and features of importance will become apparent to those skilled in the art in following the description of the illustrated form of the invention.

In the drawings:

Figure 1 is a longitudinal sectional view of the device and taken substantially on the line 1—1 of Figure 3 and in the direction of the arrows;

Figure 2 is a sectional view similar to that of Figure 1 but showing the plunger moved inwardly with respect to the body;

Figure 3 is a transverse sectional view taken on the line 3—3 of Figure 1 and in the direction of the arrows;

Figure 4 is an exploded perspective view of the component parts of the device, and;

Figure 5 is an exploded perspective view of one of the pistons.

In the accompanying drawings I have illustrated a body 10, a plunger 12, a coupling 14, a cover 16, a plurality of pistons 18 and a plurality of springs 20. These components form the essential parts of the device and are seen individually in Figure 4 and in assembly in Figures 1 and 2.

The plunger 12 is provided with a threaded coupling 24 at its outer end and in the shank portion thereof, the threaded coupling 24 being adapted to connect to a conventional drill shank 26. The shank 27 of the plunger terminates in a head 28 which is located in the cover 16 and specifically, in the concavity 30 defined in part by the cover 16 and by the top part of the body 10, the cover 16 being threaded as at 32 to a reduced part of the body 10 and held fastened in place by additional locking means, preferably the set screws 34. Accordingly, the cover 16 constitutes a part of the body 10 when the cover is assembled with the main body block.

There is an inwardly extending flange 36 provided at the top of the cover 16, this flange constituting a means of limiting the extent of outward movement of the plunger head 28 with respect to the body 10 inasmuch as the body supports the plunger in such a manner that the plunger is reciprocable with respect to the body. A conventional O ring type seal 38 is located in a groove

2

formed in the flange 36 and arranged to contact the outer surface of the shank 27 of the plunger 12.

The coupling 14 is provided with internal threads 40 to which a conventional drill bit schematically indicated 5 at 42 is adapted to fasten. Any suitable type of drill bit may be used in connection with the device, the choice being left within the prerogative of the user of the device and within his sound discretion. The upper end of the coupling 14 is threaded to a skirt 10 44 which is formed at the lower end of the body block and there is a seal 46 fastened at the junction of the coupling 14 and the main body block. When the coupling 14 is connected with the main body block, it constitutes a part of the body.

The device is adapted to be used in connection with shanks 25 which have a central liquid conducting passage therein inasmuch as the piston 12 has a central passage 48 extending therethrough, the passage being in axial alignment with the bore 50 of a sleeve 55 which 20 is fixed to the head 28 of the plunger as an axial extension thereof. The body 10 has a bore 52 therein and there is a counterbore 54 at the upper end of the bore 52, this counterbore receiving the sleeve 55 and the bore 52, the bore 50 and counterbore being in axial alignment with the passage 48 to permit free flow of water therethrough.

The head 28 of the plunger 12 is provided with a plurality of chambers 56 arranged parallel to the longitudinal axis thereof. In axial alignment with the chambers 56 and formed in the body 10, there are a plurality of chambers 58, the latter chambers retaining a fluid of proper choice, as oil, water or glycerin base fluids, which is to be used in connection with the hollow casings 60 which constitute a part of the pistons 18. The casings are cylindrical and are fixed by conventional means within the chambers 56 and are slidable in the chambers 58 when the plunger 12 is moved with respect to the body 10. Each piston has a fluid chamber 62 in it and a closure 64 for the chamber, the closure having an orifice 66 therein which opens into the chamber 62 and also into the chamber 58. A conventional wiper 70 which may be made of leather, rubber or other suitable material, is fastened to the lower end of each casing and overlies the outer wall of the closure 64 which is exposed to the walls of the lower chamber 58.

Means, for example the springs 20, are provided between the body 10 and the plunger 12 in order to constantly, yieldingly press the plunger 12 outwardly of the body to the limit of outward movement of the plunger occasioned by the presence of the flange 36 which constitutes a limiting stop. The springs 20 are preferably located in recesses 74 and 76 which are respectively formed in the body 10 and the plunger head 28 in order to hold them centered in place within the device.

In operation the coupling threads 24 are applied to the existing threads of a standard drill shank 26. After a properly selected bit 42 is connected with a coupling 14, the drill is in readiness for operation. When the bit 60 is jarred due to normal drilling operations, instead of the jar being transmitted abruptly to the shank 26, the shock is absorbed inasmuch as the body 10 moves upwardly with respect to the plunger 12 causing the fluid 65 in the chamber 58 to move through the restriction or orifice 66 into the chamber 62. This provides a dashpot action; however, the movement of the body with respect to the plunger is opposed by the springs 24. Accordingly, after the initial shock has been absorbed and the body 10 moved upwardly with respect to the plunger 12, the springs 20 will return the body to its normal extended position.

Having described the invention, what is claimed as new is:

1. A device to hold a drill bit on a shank, said device comprising a body provided with a cavity, a plunger having means at one end adapted to fasten to a drill shank and a head at the opposite end which is disposed in said cavity, means adapted to fasten to a drill bit at the end of said body opposite from the end of the body having said cavity, said body and said head having a plurality of aligned fluid chambers therein, casings fastened in the chambers in said head, said casings being slidably disposed in the chambers in said body, and said casings having orifices therein which open into the chambers in said body.

2. The combination of claim 1 and said plunger head having a sleeve extending therefrom, said body being provided with a liquid conducting bore, with a counterbore at one end arranged to receive said sleeve, the bore of said sleeve being in alignment with said first mentioned bore, and said plunger having a liquid passage in alignment with both of said bores.

3. A device to hold a drill bit on a shank, said device comprising a body provided with a cavity opening into one end thereof, a plunger having means at one end adapted to fasten to a drill shank and a head at the opposite end which is slidably disposed in said cavity, means adapted to fasten to a drill bit at the end of said body opposite from the end of the body having said cavity, said body and said head having aligned fluid chambers therein, casings fastened in the chambers in said head, said casings being slidably disposed in the chambers in said body, and said casings having orifices therein which open into the chambers in said body, said body and said plunger having cooperating abutment surfaces for limiting the movement of said plunger outwardly of said body, and means yieldingly urging said plunger outwardly of said cavity to the limit of plunger movement outwardly of the cavity.

4. In a device for coupling a drill bit on a shank, a body member, a sleeve secured to said body member and constituting an extension thereof, said sleeve having a reduced opening in the end remote from the body member providing an internal shoulder, a plunger having a head thereon reciprocably disposed in said sleeve, said head abutting said internal shoulder to limit the outward movement of said plunger from said body member, said body member and said head having aligned chambers therein, hollow casings mounted in some of the chambers in said head and being slidably engaged in the

aligned chambers in said body member, the body member chambers constituting fluid chambers resilient members urging said head toward said internal shoulder seating in the remaining aligned chambers, said casings having orifices therein opening into said body member chambers whereby the sliding movement of the casings will be resisted by fluid pressure within the chambers.

5. In a device for coupling a drill bit on a shank, a body member, a sleeve secured to said body member and constituting an extension thereof, said sleeve having a reduced opening in the end remote from the body member providing an internal shoulder, a plunger having a head thereon reciprocably disposed in said sleeve, said head abutting said internal shoulder to limit the outward movement of said plunger from said body member, said body member and said head having aligned chambers therein, casings mounted in some of the chambers in said head and being slideably engaged in the aligned chambers in said body member, resilient members urging said head toward said internal shoulder seating in the remaining aligned chambers, said casings constituting hollow pistons adapted to receive fluid, said casings having reduced orifices opening into the body chambers and including wipers contacting the walls of said body chambers, said body chambers constituting fluid chambers whereby sliding movement of the casings thereinto is resisted by fluid pressure within the chamber.

6. In a device for coupling a drill bit to a shank, a body having a cavity, a plunger provided with a head slidably disposed in said cavity, and means for arresting shock operatively connected with said plunger and said body, said arresting means including a piston secured to said plunger head, said body having a fluid chamber therein opening into said cavity slidably receiving said piston, said piston comprising a casing having an orifice opening into said fluid chamber so that movement of the plunger with respect to said body is opposed by fluid in the fluid chamber passing through the orifice into the casing.
